UNITED STATES PATENT OFFICE

CHARLES A. ELTAG, OF MILWAUKEE, WISCONSIN

CONDIMENT CONTAINER

Application filed June 10, 1926, Serial No. 114,951. Renewed August 20, 1930.

This invention relates to certain new and useful improvements in condiment containers and refers more particularly to a combined salt and pepper shaker.

5 It is an object of this invention to provide an improved condiment container having two compartments the discharge spouts of which extend in opposite directions so that when one is discharging the other extends upwardly to prevent the discharge from its compartment.

Another object of this invention resides in the provision of an improved condiment container having two compartments, the 15 spouts of which curve in opposite directions and are so disposed as to preclude the discharge of the contents of both compartments at one time.

A further object of this invention resides 20 in the provision of an improved condiment container having two or more sections or compartments molded, cast, blown, or formed from stampings.

And a still further object of this invention resides 25 in the provision of an improved condiment container of the character described which is practical and ornamental.

With the above and other objects in view which will appear as the description proceeds, 30 my invention resides in the novel construction, combination and arrangement of parts substantially as hereinafter described and more particularly defined by the appended claim, it being understood that such changes 35 in the precise embodiment of the herein disclosed invention may be made as come within the scope of the claim.

In the accompanying drawing, I have illustrated one complete example of the physical embodiment of my invention constructed 40 according to the best mode I have so far devised for the practical application of the principles thereof, and in which:

Figure 1 is a view in side elevation of a 45 condiment container embodying my invention, and

Figure 2 is a transverse section taken through Figure 1 on the plane of the line 2—2.

50 Referring now more particularly to the

accompanying drawing in which like numerals designate like parts throughout the several views, the numeral 5 designates the body portion of a two compartment condiment container having two sections or compartments 6 and 7, separated by a partition or wall 8. A discharge spout 9 having a perforated cap 10 extends from each compartment to provide means for permitting the discharge of the compartment contents. 55 The bottom wall 11 of the body portion of the condiment holder is flattened to permit the standing of the container as illustrated in Figure 1.

The condiment holder may be molded, 60 stamped or blown, and in the drawing is illustrated as stamped in two sections each having an inner flat wall 12 adapted to abut the other section and secured thereto by a pressed-out portion or button 13 on one wall, 70 having a tight, snap fit in a pressed-in portion or recess 14 in the other wall. One or more off-set portions 15 may be formed in the button 13 to engage a complementary notch 75 or off-set in the recess to prevent the rotation of the sections, in the event the portions 13 and 14 are substantially round.

As illustrated, the portions 13 and 14 may be of approximately snap button construction with an annularly peripheral bead 16 on 80 the portion 13 engaging in an annular groove or channel 17 in the portion 14. As previously stated the sections 6 and 7 may be independently formed in any desired manner, the usual construction being to form each section 85 in halves secured together, as at 18.

The spouts 9 curve laterally in opposite directions and are so disposed that when one is in a discharge position, the other extends upwardly to prevent the discharge of its associated compartment, thus providing a very 90 simple but efficient condiment container with sufficient guard against the simultaneous discharge of both compartments.

From the foregoing description taken in 95 connection with the accompanying drawing, it will be readily apparent to those skilled in the art to which an invention of this character appertains, that I provide a very novel and improved condiment container adapted 100

for use with salt and pepper, or the like, which is extremely simple but ornamental in construction, and which lends itself to quantity production at comparatively low cost.

5   What I claim as my invention is:

The combination with a condiment container having a flattened side provided with a depression having an overhanging margin, a portion of the depression and margin being non-conforming to the general contour of said depression; of a second condiment container having a flattened side provided with a raised portion positioned in and complementary to the depression and to the non-conforming portion of the depression, said raised portion having an overhanging margin interlocked with the first mentioned margin, said containers having their discharge spouts disposed in opposite directions.

10   15   20   In testimony whereof I affix my signature.
CHARLES A. ELTAG.
